United States Patent Office.

EDWARD H. ZITZMAN, OF PHILADELPHIA, PENNSYLVANIA, ASSIGNOR
TO ALBERT A. FREEMAN, OF SAME PLACE.

Letters Patent No. 99,515, dated February 1, 1870.

IMPROVED RAILWAY-BRAKE SHOE.

The Schedule referred to in these Letters Patent and making part of the same.

To all whom it may concern:

Be it known that I, EDWARD H. ZITZMAN, of the city and county of Philadelphia, and State of Pennsylvania, have invented a new and useful Improvement in "Brake-Shoes;" and I do hereby declare that the following is a full, clear, and exact description of the construction and operation of same, reference being had to the accompanying drawings, making a part of this specification, in which—

Figure 1 is an edge view of a brake-shoe, with the sole attached.

Figure 2 is a side view of same.

Figure 3 is a sectional view, broken, of the lower part of same.

The object of my invention consists of a simple and effectual arrangement, whereby the sole is kept in contact with the shoe, without the aid of bolts, keys, or springs, and at the same time prevents any lateral or longitudinal motion of the shoe when the sole is applied to the tread of a car-wheel; also, by the peculiar construction, the shoe can be readily removed from the sole when it is desired to change it.

To enable those skilled in the art to make and use my invention, I will now proceed to describe its construction and operation.

To unite the shoe and sole together, I form on the back and upper part of the sole S, a hook, H, made in the form as shown in the drawings. The said hook H passes through a rectangular opening, O, made in the upper part of the shoe B, and on the upper edge of the opening, an oval-shaped lug, F, is formed, which fits into the hook H, and holds the shoe B firmly against the sole S, and thus prevents all motion. On the back, and near the lower end of the sole S, is cast or attached a circular lug, L, in the centre of which a wrought-iron stem, T, is secured. The said stem projects a short distance beyond the end of the lug L, and bears on it an elliptical, or any suitable-shaped button, D. The button D is placed on the lug L, eccentric

to it; and in order to retain it in place, and at the same time to allow it to be turned in any direction, a countersink is formed in the outer edge of the opening, through which the stem T passes, and the end of it (the stem) is riveted into the countersink.

The lower part of the shoe B, has formed through it, opposite the lug L, an opening, N, corresponding in shape to the button D.

In applying the shoe B to the sole S, the rectangular opening O in the shoe is placed over the hook H, and the lower end of the shoe at the same time being pressed toward the sole, so that the button D is inserted through the opening O. The button is then turned, so that the projecting part will extend over and catch on the outside of the shoe B. In this position the shoe will be held, and cannot become detached from the sole. When it is desired to remove the shoe, the button D is turned around, as shown by red lines, fig. 3, so that it will correspond with the opening N; the shoe is then raised slightly, and slipped over the button D and hook H.

In forming the opening N, the conjugate diameter should equal the diameter of the circular lug L, so that this part of the opening will fit the lug, and prevent all lateral motion.

Having thus described my invention, its construction, and operation,

What I claim, and desire to secure by Letters Patent of the United States, is—

The mode of attaching the shoe B to the sole S, by means of the hook H, lug F, lug L, opening N, opening O, stem T, and button D, substantially in the manner and for the purpose specified.

In testimony whereof, I have hereunto signed my name, in the presence of two subscribing witnesses.

ED. H. ZITZMAN.
